UNITED STATES PATENT OFFICE.

WILLIAM S. PATES, OF ALTON, ILLINOIS.

CULTIVATOR.

SPECIFICATION forming part of Letters Patent No. 353,000, dated November 23, 1886.

Application filed May 29, 1886. Serial No. 203,636. (No model.)

To all whom it may concern:

Be it known that I, WILLIAM S. PATES, of Alton, in the county of Madison and State of Illinois, formerly of Jonesburg, in the county 5 of Montgomery and State of Missouri, have invented a certain new and useful Improvement in Cultivators, of which the following is a full, clear, and exact description, reference being had to the accompanying drawings, forming part of this specification, and in which—

Figure 1 is a side elevation of my cultivator, part in section. Fig. 2 is a top view of the same. Fig. 3 is a detail perspective view of 15 the horizontal bail attachment on which the vertical bail has lateral adjustment. Fig. 4 is a detail perspective view of the vertical bail provided with a bolt on which the clevis has vertical adjustment. Fig. 5 is a detail perspective view of the draw-head and clevis that 20 couple the bails to the gangs. Fig. 6 is a perspective view of the forward hanger-arch, showing its attachment to the beams from which it is suspended, and a horizontal bail 25 with its bell-crank arm and push-spring.

My invention relates to improvements adapted to both riding and walking cultivators to facilitate their adjustment by the operator when either riding or walking; and my invention consists in features of novelty herein- 30 after fully described, and pointed out in the claims.

Referring to the drawings, in which similar letters of reference indicate like parts, A represents the rear extension of the tongue, and B the frame, to the longitudinal inside bars, B', of which the gang-elevating levers C and seg- 35 ment-racks D are secured. B' represents the outside longitudinal bars of said frame.

The lever C is pivoted at C' to the base- 40 plate of the rack, and is provided with a stiff elbow-bar or short arm, C'', which descends vertically from said lever and has a pivot- bearing, C', that is adjustable in elongated 45 slots E' in the arms of the fork E' of the rod- link E. The rod terminates at its front end with a second fork, E'', whose arms embrace an upwardly-extending arm, F', and has piv- 50 oted connection at F'' with both the vertical arm F' of the horizontal bail F of the gang attachment, (see Figs. 3 and 6,) and with a vertical spring-bearing rod, H. The upper

end of the spring-bearing rod passes through and is loosely held in an eyebolt, H', that is secured to the aforesaid longitudinal bars B' 55 of the frame.

I is a spiral push-spring mounted on the rod H, to assist the operator relatively both in the elevation and depression of the gangs in its two positions. (Shown at I' in dotted lines 60 in Fig. 1.)

G is the vertical bail, (see Figs. 4 and 6,) that is supported by cleats g on the plate f, within the horizontal bail F, to which it is set and laterally adjusted by a screw-bolt, G'', that 65 passes through a perforation, G', in the vertical bail and finds lateral adjustment in an elongated slot, F', in the plate f of the horizontal bail, and is secured by a nut, g'. By this means the gangs are adjusted laterally and 70 rigidly secured in said adjustment by said screw-bolt when the nut is tightened thereon.

G' is the vertical draft-bolt attached to the vertical bail, which gives setting play for the vertical adjustment of the gangs, which ad- 75 justment is clamped by the clevis J, that has a pair of cheek-plates, J', which are closed by a set screw, J''. The clevis-bracket is secured between the fore ends of the gang-beams by bolts J', and has flanged grips J'', that clamp 80 over the edges of said beams.

K are the gang-beams, operated, when used as a walking-cultivator, by the handles L, that are bolted to them and braced by bars L', and when as a riding-cultivator by the opera- 85 tion of the lever in conjunction with the stiff- bail coupling for elevating and depressing the gangs, as will be more fully described herein- after.

M are the shovel blocks or brackets that 90 couple the shovels N to the bent beams.

O is the double-crank frame, forward arch, or hanger, on which the horizontal bails have their pivoted bearings, and on which are hooked the draw-rods P. The arch is secured to the longi- 95 tudinal bars B' of the frame by bearing-plates O'. (See Fig. 6.) A pendent vertical hitch- bar Q is provided with a series of holes, Q', for the attachment of the whiffletrees at ad- justable heights of draft.

Brace-rods R extend from the spindles or arms O' of the hanger-arch to the main axle- arch S, to which they are bolted where said axle grasps the shoulders of the spindles T,

that carry the wheels U. V represents a spring at the rear of the tongue, that carries the seat W. A pawl, X, is operated for withdrawal by the rod Y and trigger Y' and returned to 5 its engagement in the rack under the projectile influence of the spring Z.

In operating the cultivator it will be seen that the lever with its pendent extension adjusts the position of the spring-bail gang-coupling attachment, which is of peculiar construction, so that when in the projected position shown in dotted lines at 1 the stiff bail elevates the gangs even to the extent, if required, of withdrawing the shovels from the ground 15 under the influence of the depression of the lever, and when in the withdrawn position shown in dotted lines at 2 the gangs are correspondingly depressed.

A projecting lug or bolt on the pendent arm 20 C² of the lever is adjustable in an elongated slot in a rod-link that has pivoted connection with the vertical arm of the horizontal bail F. This arm has a stiff elbow-connection with the bail, and is pivoted at said elbow to the arm, 25 O' of the hanger-arch, so it is evident that when the lever is depressed and the head of the bail-arm is projected, as shown in dotted lines, the stiff-bail coupling of necessity must raise the gangs, and so also, vice versa, by the 30 elevation of the lever the shovels are depressed. The push-spring I helps the operator to make the adjustment in both cases. It will be seen (see Fig. 2) that this bail-coupling is distinct in its application from a sleeve-coupling having 35 two separate bearings on the shaft of the hanger-arch, and so obtains a much firmer and better braced hold than any sleeve could have; also, the bail has an elongated slot that gives means for the lateral adjustment of the gangs. 40 beam, and the vertical bail G carries a bolt with sufficient play for the coupling-clevis to give vertical adjustment to said gangs. Thus when used as a riding-cultivator the operator is enabled easily to command and vary the 45 elevation of the gangs without alighting from his seat or stopping the team. This is a feature of considerable importance where the change of level and the nature of the soil vary, as they frequently do in different parts of 50 the same field; also, by its adjustable bail in contradistinction to a sleeve-coupling it possesses facilities for both lateral and vertical adjustment, which, being regulated at the draft end of the gang-beams, avoids in a large degree the difficulties arising from the side draft, 55 &c., in the work of the shovels.

Although so well adapted for a riding-cultivator, it may also be used as a walking-cultivator, either with or without the use of its 50 levers, and in that case the adjustable spring-bails will still greatly aid the operator in handling the gangs; also, when used as a walk-

ing-cultivator the lug from the pendent arm of the lever, which at other times is adjusted to the position desired and firmly secured by 65 a tight nut in the elongated slot E' of the rod-link E, may, by loosening the nut, become self-adjusting in the slot and give more freedom to the operator in the use of the handles.

I claim as my invention—

1. The combination of a suitable supporting-frame, a lifting-lever, a hanger provided with a horizontal spindle, a horizontal bail having an upwardly-extending arm, a hinged spring-rod, a rod connecting the lever with 75 the arm, a clevis, J, and a vertical bail, G, by which the clevis and horizontal bail are connected together, substantially as described.

2. The combination of a suitable supporting-frame, a hanger provided with a horizontal spindle, the horizontal bail F, hinged on the spindle, a vertical bail, G, sliding sideways on the horizontal bail, and a clevis, J, connected to the horizontal bail by means of the vertical bail and adjustable vertically on 80 the latter, substantially as described.

3. The combination of a suitable supporting-frame, a hanger provided with a horizontal spindle, the horizontal bail F, having an upwardly-extending arm, F', and hinged 90 on the spindle, a vertical bail, G, to the rear of the horizontal bail and sliding sideways thereon, having rear arms provided with a vertical bolt, G', and a clevis, J, to the rear of the vertical bail and sliding vertically thereon; 95 substantially as described.

4. The combination of the horizontal bail having an upwardly-extending arm, a bearing-rod, a spring surrounding the bearing-rod, and a lever connected to the arm, substantially 100 as described.

5. The combination of a hanger provided with a horizontal spindle, a horizontal bail having an upwardly-extending arm and hinged to the spindle, a bearing-rod, a spring, 105 a lever, and a rod connecting the lever with the arm and bearing-rod, substantially as described.

6. The combination of a suitable frame, a hanger having a horizontal spindle, a horizontal bail, F, hinged on the spindle having an upwardly-extending arm, F', and formed with a slot, F', in its rear plate, a vertical bail, G, to the rear of the horizontal bail adjustable on the rear plate, the bolt G², and nut 110 g', for securing the vertical bail, the vertical bolt G', secured in the arms of the vertical bail, and a clevis, J, to the rear of the vertical bail and adjustable on the vertical bolt of the latter, substantially as described.

WILLIAM S. PATES.
